COTTON CONVEYER

William H. Suttenfield, Statesville, and Olin L. York and Van Buren A. Howard, Longisland, N. C., assignors to Superior Yarn Mills, Incorporated, Statesville, N. C., a corporation of North Carolina

Application June 8, 1934, Serial No. 729,692

1 Claim. (Cl. 19—67)

This invention relates to a machine for cleaning and conveying cotton and more especially to an elongated tube with a plurality of beaters therein which not only loosens up the cotton so that the dirt and trash will be removed therefrom but also conveys the cotton from one machine to another at the same time.

In the opening rooms of cotton mills where the bales of cotton are opened up the loose cotton is conveyed to the picker room through a long conveyer pipe by suction. This operation draws in dust and causes more dirt and trash to be in the cotton. The present invention does not work on a pneumatic principle but conveys the cotton through the elongated tube by means of a plurality of rotary beaters which loosen the cotton and allows the trash and dirt to fall through a suitable grate or grid bars disposed in the lower portion of the tube, thereby separating the trash and dirt from the cotton.

It is therefore an object of this invention to provide a cotton conveyer which will convey the cotton from one point to another and at the same time remove objectionable matter such as trash, dirt and motes therefrom.

It is a further object of this invention to provide a cotton conveyer which is efficient and economical to operate. By actual experiment it has been found that after the cotton has been passed through the conveyer and placed in conventional pickers, fully fifty percent more trash has been removed from it than cotton which has been conveyed by pneumatic means. This increased efficiency is due to the fact that the cotton is loosened up and fluffed in this invention whereas, pneumatic means has a tendency to form the cotton into lumps. It has also been found by experiment that much less power has been required to operate the machinery in the picker room when this conveyer is used due to the excellent working state of the cotton.

Some of the objects of the invention having been stated other objects will appear as the description proceeds when taken in connection with the accompanying drawings, in which:

Figure 1 is a plan view of the invention connected to a conventional bale breaker and a vertical opener;

Figure 2 is a sectional view taken along the line 2—2 in Figure 1;

Figure 3 is a sectional view taken along the line 3—3 in Figure 1;

Figure 4 is a sectional view taken along the line 4—4 in Figure 1;

Figure 5 is an enlarged transverse sectional view taken along the line 5—5 in Figure 4;

Figure 6 is an enlarged longitudinal view taken along the line 6—6 in Figure 5;

Figure 7 is a sectional view taken along the line 5—7 in Figure 1;

Figure 8 is a longitudinal sectional view showing the invention operating with a bale breaker and lattice opener.

Referring more particularly to the drawings, 10 the numeral 10 denotes a conventional bale breaker which has an apron 11 upon which the cotton is placed when it is removed from the bale. The cotton passes from apron 11 to pin apron 12 (see Fig. 8), under pin cylinder 13, and by doffer 14. The arrangement of parts in Figure 1 is particularly adapted to clean short staple cotton; therefore, after the cotton has passed through the bale breaker 10 a section of a cleaner and conveyer is secured to the end of the bale breaker 15 which conveys the cotton to a conventional vertical opener 15.

By referring to Figure 4 it is seen that this conveyer is comprised of an elongated rectangular tube 16 which is reinforced with suitable corner angles 17, 18, 19 and 20. Secured to the outer portions of the sidewalls of tube 16 are angles 21 and 22 which serve as reinforcing members and also as supports for the bearings 23 and 24. All of these bearings are identical and will be given like reference characters. Fixedly mounted in each of bearings 23 and 24 is a sleeve 25 in which is rotatably mounted a shaft 26, said shaft 26 having fixedly secured thereon a pair of truncated conical members 27 by any suitable means such as set screw 27a. Sleeve 25 projects several inches into hub 27 in order that the oil which may be used for the lubrication of the bearings 23 and 24 will not escape and damage the cotton. Since the small end of cone 27 fits tightly against the sidewalls of the tube and the sleeves 25 project a substantial distance into the hubs, there is practically no seepage of oil on the inside of tube 16. The right-hand end of tube 16 is supported in its proper relation to vertical opener 15 by suitable supports 33, whereas the left-hand end is likewise supported with relation to bale breaker 10 by supports 34, (see Fig. 4).

Mounted on the large ends of cone shaped members 27 is a cylinder 30 in which is threadably secured a plurality of prongs 31. These prongs rotate with the cylinder and loosen the cotton as it is conveyed. By having a smooth cylindrical rotating surface there is no danger of the cotton becoming entangled with the conveying appa- 55

ratus and causing unnecessary wear and trouble.

Secured to the inside of the sidewalls of tube 16 is a pair of angles 35 and 36 upon which is mounted a grate 37. It is seen that the top edge 5 of the grate bars are wedge-shaped and inclined towards the direction of rotation of the lower side of the cylinder so that the dirt, trash, stones and the like will easily pass between the bars and into the lower compartment 38 of the tube.

10 A plurality of cleanout doors 39 are located in suitable places in order that the refuse matter may be removed from compartment 38.

The upper compartment likewise has suitable windows 41 spaced at desired intervals so that the 15 operation of the conveyer may be viewed without removing the cover. Disposed on top of the conveyer are a plurality of inspection doors 42 which will allow one to have access to the inside of the tube.

20 The shaft 26, on the extreme left-hand end of Figure 4, has mounted on the end thereof a pulley 45 which is adapted to be driven by a suitable belt, not shown (see Fig. 7). A sprocket 49 is also fixedly secured on this shaft and has mounted 25 thereon a chain 51, said chain 51 being also mounted on a similar sprocket 49 on the next shaft 26, to the right in Figure 4. All of the shafts 26 which are mounted in conveyer 16, except the end shafts, have two sprockets 49 and 50 30 fixedly mounted thereon. Mounted on each pair of sprockets 49 is a chain 51 and mounted on each pair of sprockets 50 is a chain 52.

It is seen when the pulley 45 rotates that each of the shafts 26 will also rotate since they are 35 hooked up in series; therefore, the cylinders 30 and prongs 31 will rotate to loosen up the cotton and transfer it at the same time.

When the cotton has reached the right-hand end of conveyer 16, (Fig. 4), it is conducted by 40 pneumatic means through the spout 53 in the conventional vertical opener 15. After passing through the machine it is passed from the apron 54 to another section of cleaner and conveyer tube 55 to the picker apron 56.

45 Conveyer tube 55 is supported at its proper elevation by any suitable means such as supports 57 and 58. The construction of this tube is similar to tube 16 and another description is not deemed necessary but like parts will bear like reference 50 characters and the exceptions in the construction will be described.

The extreme left-hand shaft 26 in Figure 3 is similar to shaft 26 as shown in Figure 7 and has a pulley 60 fixedly secured on the end thereof and 55 also a sprocket 49. Pulley 60 is driven by belt 61 which is mounted on pulley 62, said pulley 62 being fixedly mounted on conventional opener shaft 63. Likewise, in this conveyer each shaft 26 except the end ones, has a pair of sprockets 49 60 and 50 fixedly mounted thereon and each pair of sprockets 49 are connected by a chain 51 as well as each pair of sprockets 50 are connected by a chain 52. The end shafts have inner sprocket 49 mounted thereon but do not have a sprocket 50. 65 It will be noted that conveyer 55 has its right-hand end (Fig. 3) inclined upwardly in order that the cotton may be more thoroughly cleaned before it is delivered to the picker.

When the cotton reaches the right-hand end of conveyer 55 it falls through opening 65 onto the apron 56 of the picker. When the picker stops to doff, a certain amount of overflow occurs in conveyer 55; consequently, the opening 65 will be 5 filled up. In order to take care of this overflow, a suitable conveyer 66 is provided which has rotatably mounted therein shafts 67 and 68 having rollers 69 and 70 respectively mounted thereon. Upon these rollers is mounted a belt 71 which has 10 a plurality of prongs 72 secured thereto which engage the overflow cotton that is thrown on the belt 71 and convey it back to the apron 11 of the bale opener 10. This arrangement prevents the choking up of the conveyer 55. Shaft 68 has a 15 pulley 75 fixedly mounted on the end thereof which is driven by a suitable belt, not shown. It is evident that as shaft 68 rotates the conveyer belt 71 will also rotate.

The right-hand end of conveyer 66 is supported 20 by any suitable means such as posts 76 and the left-hand end is supported by the end of conveyer 55.

Figure 8 shows another combination of machines with which this conveyer is adapted to be 25 used. This arrangement consists of a bale breaker 10, a section 78 of the conveyer, a lattice opener 79 and the picker. The parts in the conveyer 78 are identical to the parts described in conveyer 16 and will bear like reference characters. It 30 has been found in cleaning long staple cotton that a cleaner and conveyer 78 of about seven feet in length is used to the best advantage whereas, if short staple cotton is used about ten feet will produce better results. 35

In the drawings and specification there has been set forth a preferred embodiment of the invention, and although specific terms are employed, they are used in a generic and descriptive sense only, and not for purposes of limitation, the 40 scope of the invention being set forth in the appended claim.

We claim:

Fiber preparation machinery comprising a bale breaker, an opener, and a picker, a horizontally 45 disposed endless belt for feeding fibers into the bale breaker, a tube disposed between the bale breaker and the opener and having a series of grates forming upper and lower horizontal compartments extending for the length of the tube, 50 the interior of the tube being exposed to atmospheric pressure, said tube having a plurality of driven beaters disposed transversely thereof for driving the fibers from the bale breaker to the opener, a second tube disposed between the opener and the picker and having a series of grates 55 therein forming upper and lower compartments, the upper compartment having a plurality of transversely disposed driven beaters therein for forcing the fibers from the opener to the picker, a second endless belt for conveying any surplus fibers which are not fed into the picker back and onto the top of said first endless belt whereby the surplus fibers are again introduced into the bale breaker. 60
